FILLING REPLENISHING LOOM

Carl D. Brown, Hopedale, Mass., assignor to
Draper Corporation, Hopedale, Mass., a cor-
poration of Maine

Application July 22, 1939, Serial No. 286,010

10 Claims. (Cl. 139—258)

The present invention pertains to automatic filling replenishing looms and more particularly relates to the control and removal of the incoming filling ends formed by such looms.

5 Automatic looms commonly have a reciprocating lay with a shuttle box at the replenishing end thereof, filling replenishing mechanism for automatically replenishing the filling supply, and parting means for parting the filling ends which 10 are left projecting from the cloth selvage as a result of the replenishing operation. The replenishing mechanism includes a magazine holding reserve filling carriers, with the filling ends from such carriers attached to a holder, usually on 15 the magazine. The outgoing filling ends are parted in two different places and are clamped adjacent the shuttle box. The filling ends that are attached to the said holder become the incoming filling ends as their respective filling carriers are put into operation. The incoming filling 20 ends are commonly parted at only one point, usually adjacent the cloth selvage.

The outgoing and incoming filling ends must be so controlled or withdrawn away from the 25 moving parts of the loom as to prevent their being woven into the cloth. The incoming filling end is particularly difficult to control, it being relatively long and so located that it can easily fall or be blown into the shuttle box. It 30 is with the withdrawing of this incoming end that the present invention is primarily concerned.

A principal object of the present invention is to provide an automatic filling replenishing loom 35 having a lay, magazine and parting means for the incoming filling ends, as aforesaid, and which shall also have gravity-operated means for withdrawing the parted incoming filling ends, and means operating as each such filling end is withdrawn to move or return such gravity means into withdrawing relation to the next succeeding filling end, whereby such filling ends are successively withdrawn as they are formed and parted.

45 The foregoing and other objects of the invention are accomplished in the construction illustrated on the accompanying drawings, of which:

Fig. 1 is a perspective view of the replenishing side of a loom having the preferred embodiment of my invention applied thereto;

Fig. 2 is a detail view, in section and to an enlarged scale;

Fig. 3 is an end view, partly in section, showing said preferred embodiment; and

55 Fig. 4 is a view similar to Fig. 3 but showing

the parts as they appear at a later point in the cycle of the operation of the loom.

The drawings illustrate only such part of a complete loom as is necessary to an understanding of the present invention, the parts and mechanisms not shown being of usual construction forming no part of the present invention. In addition, certain of the parts that are shown are of usual construction, they being of the present invention only as examples of elements in the 10 combination defined in the appended claims. Such usual parts include the reciprocating lay which comprises a lay beam 1 having a reed 2 and a shuttle box 3 thereon. The shuttle box 3 is at the replenishing end of the lay, which in 15 the present instance is at the right hand side of the loom.

The warp threads W feed forwardly in the loom and are separated to form a shed as shown by Fig. 1. A shuttle 4, carrying a filling carrier such as bobbin 5, is picked from side to side of the loom along the lay beam 1 to lay picks of filling thread in the successively formed shed openings. The shuttle picking mechanism may include the usual picker stick 6. The lay reciprocates forwardly and rearwardly of the loom and in so reciprocating the reed 2 beats the picks of filling into the fell of the cloth C being woven by the loom. When the filling supply on the filling carrier 5 is substantially exhausted, a fresh 30 filling supply is automatically provided by the replenishing mechanism.

The replenishing mechanism may be of any suitable usual construction, the drawings fragmentarily illustrating the well-known bobbin 35 changing mechanism including a magazine 7 and a transerrer 8. The magazine 7 contains a supply of reserve filling carriers 5' and is rotated step by step to successively present such filling carriers in position to be transferred to the shuttle 4. The filling ends f leading from the reserve carriers 5' are attached to a holder which is so related to the magazine as to be a part thereof. The particular holder 9 for the ends f is fixed directly on the end of the magazine 7. 40 The filling end f from the filling carrier 5' in transferring position extends lengthwise of the shuttle box 3 above the same.

When so required by mechanism not shown, the transerrer 8 transfers the carrier 5' in transferring position to the shuttle 4 and the shuttle is thereupon picked through the shed while the lay moves rearwardly. This picking of the shuttle and the subsequent beating of the resulting pick of filling into the fell leaves an end F of fill- 45 50 55

ing thread projecting from the cloth selvage **S** and extending to the holder **9**. The thus formed filling end **F** is known in the art as the incoming filling end. The end **F** is parted between the magazine and the cloth selvage, as by the usual temple thread cutter **10** located adjacent the cloth selvage. The parted filling end is quite long and is so located that, if uncontrolled, it is apt to fall or be blown onto or into the path of the shuttle **4** and be carried into the shed, thus forming a defect in the cloth.

The present invention provides a simple and efficient gravity-actuated means for successively withdrawing the filling ends **F** away from the lay and shuttle box, and means operating promptly after each such withdrawing operation to return the gravity means into withdrawing relation to the next succeeding thread. Such means thus removes each filling end **F**, as soon as it is parted by the temple thread cutter **10**, and thereby prevents the end from being drawn into the cloth. The prompt return of the gravity means insures that it will always be ready to withdraw the next incoming filling end as soon as the latter is formed and parted.

The aforesaid withdrawing means, being gravity actuated, may be simple in construction. The preferred form shown comprises a weight **11** having means such as hook **12** by which it is adapted to be suspended from the filling end **f** which leads from the filling carrier **5'** in transferring position. The hook **12** engages over such filling end and thereby supports the weight **11**. Thus, during normal loom operation, the weight and hook occupy the position shown by Figs. 1 and 3. In this position, the weight is adjacent the upper, rearward end of a guide **13**.

The particular guide **13** shown consists of a tube which extends from a point above the outer or right hand end of the shuttle box **3** forwardly and downwardly to a point well below and in front of the lay beam **1**. The weight **11** is freely slideable in the guide **13** and the latter is slotted longitudinally at **14** to permit the hook **12** to project therefrom. The guide **13** is fixed on a bracket **15** which in turn is fixed on the stud **16** on which the transerrer **8** is pivoted. A suitable retaining hook **17** may be carried by the bracket **15**.

The weight **11** remains suspended from the end **f** while the filling carrier **5'** from which such end leads is transferred to the shuttle **4** and the shuttle is picked. The weight thus provides a yielding tension on the filling thread during the first pick after transfer. The weight continues to remain suspended from the end **f** until after the latter has become an incoming end designated **F**, as shown by Fig. 1. Then, as soon as this end **F** is cut by the cutter **10**, the weight slides by gravity forwardly and downwardly in the guide **13**, the hook **12** pulling the cut end forwardly and downwardly into the hook **17**. When so positioned, the ends **F** are held against any possibility of being woven into the cloth.

The preferred embodiment of means for returning the weight **11** into withdrawing relation to the next succeeding filling end **f** comprises means for throwing the weight upwardly and rearwardly along the guide **13**. As shown, the throwing means may consist of a spring **18** and a member **19** for stressing the spring. The spring **18** is an open coiled spring positioned in the lower end of the guide **13** and supported at its lower end by a plug **20**. When the weight **11** slides by gravity as above described it comes to rest on top of the spring **18** as shown by Figs. 2 and 4. The member

19 is a lever which is pivoted at its upper end in a bracket **21** on the lay beam **1** and which has its lower end turned laterally at **22** to compress the spring **18** by engaging the hook **12** and pushing the weight **11** down. 5

The lever **19** is acted upon by a torsion spring **23** which is arranged to yieldingly raise the lower end **22** of the member. When the lay is back, as in Fig. 4, the end **22** is raised by spring **23** to the position determined by a stop **24**, the stop being fixed to the upper end of the lever **19** and engageable with the bracket **21**. As the lay next moves forwardly from its Fig. 4 position, the end **22** engages the guide **13** and slides downwardly along the same, the lever **19** pivoting in bracket **21** against the action of the spring **23**. With the weight **11** in its Fig. 4 position, the downwardly moving end **22** engages the hook **12** and pushes the hook and weight downwardly, thereby compressing the spring **18**. At a point near the end of the forward movement of the lay, the end **22** is cammed rearwardly away from the hook **12** by a cam **25** on the guide **13**. Thereupon, the compressed spring **18** throws the weight **11** upwardly and rearwardly in the guide **13**. 10

The aforesaid throwing of the weight **11** by the spring **18** occurs on the first beat of the lay following each downward sliding, or withdrawing, action of the weight. At all other times the end **22** slides idly on the guide **13**, the weight being at the upper end of the guide. The weight is thrown to the upper rearward end of the guide, and in so moving an inclined portion **26** on the hook **12** rides over the next succeeding filling end **f**, which is the end from the filling carrier **5'** in transferring position. After so moving, the weight slides forwardly until the hook **12** engages over the last said end **f**. At this time, the hook **12** and weight **11** are completely returned into withdrawing relation to the next succeeding filling end **f** and so remain until after the next transfer, whereupon the withdrawing action is repeated as above described. A fixed hook **27** projects toward the left from the guide **13** and prevents the weight from pulling the filling ends **f** forwardly before they are parted. 35

Having fully disclosed the preferred embodiment of my invention, I claim:

1. In an automatic filling replenishing loom, the combination of the reciprocating lay, a magazine for holding reserve filling carriers with the filling ends from such carriers attached to the magazine, means for parting said filling ends adjacent the cloth selvage, gravity-actuated means for successively withdrawing each said filling end away from the lay after it is parted, and means operating after each withdrawing operation of said gravity-actuated means to move said gravity-actuated means into engagement with the next succeeding filling end. 50

2. In an automatic filling replenishing loom, the combination of the reciprocating lay, a magazine for holding reserve filling carriers with the filling ends from such carriers attached to the magazine, means for parting said filling ends between the cloth selvage and the magazine, a gravity-actuated weight adapted to successively withdraw each said filling end away from the lay after it is parted, and means operating after each withdrawing movement of said weight to move the latter into withdrawing relation to the next succeeding filling end. 65

3. In an automatic filling replenishing loom, the combination of the reciprocating lay, a magazine for holding reserve filling carriers with the 70

filling ends from such carriers attached to the magazine, means for parting said filling ends adjacent the cloth selvage, a gravity-actuated weight having means for engagement with one of said filling ends, guide means along which said weight moves to withdraw said filling end away from the lay after it is parted, and means operating after each withdrawing movement of said weight to move the latter into engagement with the next succeeding filling end.

4. In an automatic filling replenishing loom, the combination of the reciprocating lay having a shuttle box at the replenishing end thereof, replenishing mechanism including a magazine for holding reserve filling carriers with the filling ends from such carriers attached to the magazine, said magazine being adapted to successively present said filling carriers in transferring position, a weight adapted to be suspended from the filling end from the filling carrier in transferring position to thereby yieldingly tension such filling end, and means operating after each replenishing operation to suspend said weight from the next succeeding filling end.

5. In an automatic filling replenishing loom, the combination of the reciprocating lay having a shuttle box at the replenishing end thereof, a magazine for holding reserve filling carriers, a fixed holder for the filling ends leading from said filling carriers, means for parting said filling ends adjacent the cloth selvage, gravity-actuated means for successively withdrawing each said filling end forwardly away from said shuttle box after the filling end is parted by said parting means, and means operating after each withdrawing operation of said gravity-actuated means to move said gravity-actuated means into engagement with the next succeeding end at a point above the outer end of said shuttle box.

6. In an automatic filling replenishing loom, the combination of the reciprocating lay, a magazine for holding reserve filling carriers with the filling ends from such carriers attached to the magazine, means for parting said filling ends between the cloth selvage and the magazine, a weight for successively withdrawing the parted filling ends away from the lay, a guide along which said weight moves by gravity in withdrawing said filling ends as aforesaid, and means operating after each withdrawing movement of said weight to throw said weight along said guide into withdrawing relation to the next succeeding filling end.

7. In an automatic filling replenishing loom, the combination of the reciprocating lay, a magazine for holding reserve filling carriers with the filling ends from such carriers attached to the magazine, means for parting said filling ends between the cloth selvage and the magazine, a weight having a hook by which it is adapted to

be suspended from the filling end from the filling carrier in transferring position, a guide along which said weight moves by gravity to withdraw the last said filling end away from the lay after such filling end is parted as aforesaid, and means operating after each withdrawing movement of said weight to throw said weight along said guide and engage said hook with the next succeeding filling end.

8. In an automatic filling replenishing loom, the combination of the reciprocating lay having a shuttle box at the replenishing end thereof, a magazine for holding reserve filling carriers and successively presenting the same in transferring position, a holder for filling ends from said carrier, means for parting said filling ends between the cloth selvage and said shuttle box, a weight having a hook by which it is adapted to be suspended from the filling end from the filling carrier in transferring position, a guide leading forwardly and downwardly from a point adjacent the last said filling end, said weight being adapted to move along said guide by gravity to withdraw the last said filling end forwardly and downwardly after it is parted, a spring arranged to throw said weight upwardly and rearwardly along said guide into engagement with the next succeeding filling end, and means operated by the lay for actuating said spring after each withdrawing movement of said weight.

9. An automatic bobbin changing loom having means for parting filling ends projecting from the cloth selvage and means for withdrawing the parted filling ends from the moving parts of the loom, the last said means comprising a weight adapted to successively engage said filling ends and withdraw the same forwardly and downwardly of the loom after they are parted, a guide along which said weight moves by gravity to withdraw said filling ends as aforesaid, and means operating after each said withdrawing movement of said weight to return said weight along said guide into withdrawing engagement with the next succeeding filling end.

10. An automatic bobbin changing loom having means for parting filling ends projecting from the cloth selvage and means for withdrawing the parted filling ends from the moving parts of the loom, the last said means comprising a weight having a hook by which it is adapted to successively engage said filling ends, a guide along which said weight moves by gravity to successively withdraw said filling ends forwardly and downwardly after such ends are parted, a spring arranged when stressed to throw said weight along said guide into withdrawing engagement with the next succeeding filling end, and means for stressing said spring as aforesaid after each withdrawing operation of said weight.

CARL D. BROWN. 60
